(57) **CLAIM**

The ornamental design for a wireless charger with phone ring holder, as shown and described.

DESCRIPTION

FIG. 1 is a front, right and top perspective view of a wireless charger with phone ring holder, showing our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is another front, right and top perspective view of the wireless charger with phone ring holder in another state. The broken lines depict portions of the wireless charger with phone ring holder that form no part of the claimed design.

1 Claim, 8 Drawing Sheets
